UNITED STATES PATENT OFFICE

2,273,082

MANUFACTURE OF MULTIFILAMENT
RUBBER THREADS

Lucius Dexter Aldrich, North Providence, R. I., assignor, by mesne assignments, to United States Rubber Company, New York, N. Y., a corporation of New Jersey

Application June 15, 1938, Serial No. 213,762

16 Claims. (Cl. 18—8)

This invention relates to the manufacture of rubber threads and more particularly to methods and apparatus for the production of multi-filament rubber threads having a desired cross-sectional configuration.

Various methods have been proposed for grouping or associating together a plurality of rubber threads in a tacky condition to form a continuous composite grouping of the individual filaments into a rubber tape or cord. One previous procedure for making rubber threads having a cross-section comprising an aggregate of circular configurations has been suggested in which a specially designed nozzle extrudes, substantially in contact with each other, a desired number of threads from rubber latex or a solution of rubber. The nozzle is so constructed that the individual filaments are extruded closely together, preferably converging toward a central axis, and are immediately caused to adhere or coalesce together upon emerging from the nozzle. This method obviously cannot be utilized for producing a generally flat thread in which the component filaments are to be aligned in a substantially straight row. When arranging the filaments around a central axis by such a procedure, the grouping or relationship of the threads with respect to each other is fortuitous, and cannot be accurately controlled. In practicing this procedure, it is imperative that a specially designed nozzle be utilized.

In another previous method for the production of this type of thread, a plurality of filaments are formed by depositing latex into rounded grooves around the periphery of heated wheels, and pressing the partially dried latex filaments into the desired arrangement by the use of cooperating flanged or grooved rollers. The pressure necessary in practicing this method deforms the rounded filaments into a rectangular block so that an almost unitary composite flat-sided thread is the result.

It has also been suggested to form a substantially flat grooved rubber tape, such as golf ball tape, by extruding rubber latex as a series of, 45 separate filaments, into a dehydrating and setting medium, allowing the filaments lightly to contact each other side by side as they travel through the medium, washing the tape temporarily formed by aggregation of the separate filaments, and passing the tape between two cooperating rollers which by pressure consolidate the temporary group of filaments into a final flat grooved tape. The pressure means employed in this method also deform the round filaments 50

originally extruded, flattening them at least on the opposite sides.

In accordance with the present invention, a multi-filament rubber thread, for example in the form of a cord or a tape, may readily be produced without the application of sufficient pressure at any time to alter the original cross-sectional configuration of any individual filament of the ultimate multifilament thread. The 10 invention also provides for the accurate production of a multiple filament rubber thread in which the desired cross-sectional configuration or grouping of the filaments may be accurately predetermined and accomplished.

15 The accompanying drawing represents illustrative embodiments of the invention, in which—

Fig. 1 is a plan view, with a section removed, of one side of an apparatus for forming multi-filament rubber threads;

Fig. 2 is a cross-sectional view taken along the line 2—2 of Fig. 1;

Fig. 3 is a side elevational view, partly broken away, of a grouping member and means for holding it in position;

Fig. 4 is a side elevational view, partly broken away, of an alternative grouping member;

Fig. 5 is a perspective view of a generally triangular multifilament thread produced by the apparatus; and

Fig. 6 is a perspective view of a generally flat multifilament thread produced by the apparatus.

In the present method of producing a multi-filament rubber thread, a plurality of at least partially coagulated rubber filaments of desired cross-section are drawn within a fluid medium beneath and in contact with grouping means adapted to impart the desired grouping configuration to the plurality of filaments. For example, if a substantially flat thread is desired, each group of filaments is drawn or floated within a fluid medium beneath and in contact with a forming member having a substantially flat or slightly concave lower surface. If, on the other hand, a thread of generally triangular cross section is desired, a forming or grouping member is employed in which the lower forming surface may correspond generally to the shape of an inverted V. Other grouping configurations of the filaments may be obtained by the use of grouping means or forming members having a lower surface corresponding generally to the ultimate configuration of the particular thread desired. From beneath the grouping member,

the multifilament thread initially produced thereby is preferably drawn over and in contact with a shape-retaining member having on its upper surface a configuration corresponding to that of the lower surface of the forming member. The shape-retaining member holds the component filaments of the composite thread in their proper grouping configuration so that they retain their shape and grouping arrangement permanently. It is also contemplated to provide adjustable shape-retaining means which in one position will retain the grouped individual filaments of a thread in a certain desired arrangement, and in another position will retain them in a different formation.

In carrying out the invention, a plurality of at least partially coagulated rubber filaments may be produced in any desired manner, as by streaming latex through a plurality of regularly arranged nozzles of desired shape and dimensions into a coagulant. Other methods of forming the individual filaments may also be employed, for example, as by streaming or extruding a dispersion or solution of rubber into a drying and setting medium, or by streaming filaments of heat sensitive latex into a heating medium at least to initiate coagulation thereof, or by any other known or desired process. The separate filaments in their tacky or partially coagulated state are then drawn through any suitable fluid medium, which may be the coagulant itself, or hot water in the case of a heat sensitive latex, or any desired fluid of higher specific gravity than the partially coagulated rubber filaments. The grouping means for each group of filaments are preferably in the form of a bar or rod positioned within the fluid medium transversely to the direction of travel of the filaments as they emerge from the nozzles. As the filaments are drawn through the fluid medium beneath the grouping bar, they tend to float and since they are of lower specific gravity than the fluid medium, they rise into contact with the grouping surface of the forming or grouping member. Before arrival under the grouping member, the filaments are preferably aligned vertically, as by means of a staggered row of pins or rods which may conveniently project upwardly through the fluid medium. These vertical aligning means permit the desired number of filaments to be proximately positioned into a group immediately prior to their formation into the composite thread. Each group of filaments is then drawn beneath the forming member.

The lower surface of the forming member is substantially horizontal and is preferably slightly concave when a substantially flat thread is desired. As the filaments are impelled upwardly against this surface by reason of their buoyancy within the fluid medium, they become associated into a substantially flat or slightly concave group, depending upon the degree of curvature of the lower surface of the member. By reason of their tacky or partially coagulated condition, each filament adheres to that or those adjacent to it, thus forming the composite thread, the individual filaments of which are aligned according to the shape of the lower surface of the grouping member. This alignment is retained and adhesion is assisted by subsequent contact with the upper surface of the shape-retaining member. The pressure exerted by reason of the buoyancy of the filaments against the grouping member or their contact with the shape-retaining member

is insufficient to deform them, yet they retain their initial association with each other.

When a grouping or forming member having a generally triangular lower surface is employed, as for example when shaped like an inverted V, one of the filaments contacting against it will naturally assume a position closest to the apex, while the other two become horizontally aligned below and in contact with it. If the angle of the V approximates 60° or is of slightly greater angularity, all three filaments will be in contact with each other, resulting in a composite thread having an equilaterally triangular grouping arrangement corresponding to the V shaped groove.

15 The number of filaments to be arranged into a permanent composite thread, however, is not limited to three. For example, if six are employed, they may be initially, upon their introduction below the member, arranged also in triangular configuration, after which successive corresponding portions of the length of each of the filaments will tend to assume the same grouping as they pass beneath the grouping bar. After withdrawal from the V-groove in the forming or grouping bar, the thread is drawn over the shape-retaining member in a similar groove which holds the individual threads in the same composite grouping relationship while they become adhered to each other.

30 In practicing the invention to produce generally triangular multifilament threads, a set of V-grooved grouping or forming members is inserted in position in the apparatus. Each forming member is placed in alignment with a group of 35 individual filaments which are brought together in generally triangular relationship beneath the member in the groove. The shape-retaining member is provided with V-shaped grooves which alternate with flat or slightly concave upper 40 forming surfaces, and is so adjusted that the V-shaped upper grooves register in alignment with each of the lower V-shaped grooves in the forming bars. The composite thread is thereby held in the proper form as it travels in the upper 45 grooves of the shape-retaining member.

When it is desired to form a multifilament thread having a generally flat or slightly concave cross-section, a different set of grouping bars or members is substituted for the V-grooved bars. 50 These alternative bars may be flat on their lower surfaces, but are preferably slightly concave. When employing this alternative set of flat-surfaced forming members, the position of the shape-retaining member is shifted so that the 55 flat or slightly concave upper surfaces thereof register in alignment with the forming or grouping bars to hold the filaments in proper position within the thread while they are adhered to each other.

60 Referring particularly to the drawing, Figs. 1 and 2 illustrate a suitable apparatus arranged to produce multi-filament rubber threads of generally triangular cross-section. In Fig. 1, only one side of the apparatus is shown, since the opposite side may be identical therewith. A tank 1 open at the top contains a fluid 2, preferably acetic acid or other coagulant for rubber latex. Groups of nozzles 3, having preferably circular jets, are positioned within the fluid near one end 65 of the tank substantially parallel to the length of the tank, and are supplied from a latex source (not shown) by pipes 4. Three nozzles are illustrated as emerging from each pipe, although it is obvious that any desired number may be supplied, according to the number of filaments de-

sired in each finally formed thread. One latex filament 5 is streamed from each of the nozzles 3.

Each group of filaments 5 is compositely associated by the apparatus into a multifilament composite thread 6 in a manner described hereinafter. At the opposite end of the tank 1 a roller 7 is mounted above the top of the end wall of the tank by means of brackets 8, to provide egress for the composite threads 6. Means (not shown) are provided to withdraw the threads 6 from the tank at the desired rate of speed.

Intermediate of the ends of the tank is a removable plate 10 which is positioned transversely of the line of direction of the filaments 5 and is provided with legs 11 which rest upon the bottom of the tank. Pins 12 and 13 extend upwardly from the plate 10 to provide means for vertically aligning each group of filaments 5. The pins 12 and 13 are staggered relative to each other, but are generally located along the lines of direction of travel of the filaments. Between the aligning pins and the egress side of the apparatus, grouping or forming bars 15, shown in detail in Fig. 3, are horizontally positioned so that each lies along the path of travel of a filament. Each grouping bar 15 is provided with a central V-shaped groove 16, which may conveniently circumscribe the generally cylindrical bar, or may be formed only in the lower portion of the bar. Lateral grooves 17 extend parallel to each other part way along each end of the bar to engage pins 18, a pair of which hold each bar 15. A handle 20, conveniently in the form of a rod which extends well above the level of the liquid 2, is secured in the top of each bar 15 so that the bar may be lifted out. The pins 18 are mounted within, and extend vertically upward from, an adjustable base 21.

The base 21 has a slot 22 near each end through which a bolt 23 carrying a flange 24 extends to secure the base 21 adjustably relative to the plate 10. The lower end of the bolt 23 is screwed into a threaded hole toward the end of plate 10, and the base 21 rests slidably on the flange 24, and may be secured in position by the nut 25. A screw-driver slot is provided in the top of the base 21, which may be effected by also loosening the nuts 25 at each end of the base, so as to change the position of the bolts 23 in the slots 22, whereupon the nuts 25 may be again tightened. This adjustment is desirable in order to align the bars 15 in proper relationship with the line of travel of the filaments 5, after they pass the aligning pins 12 and 13 respectively.

Parallel to the plate 10, and between the plate 10 and the egress end of the tank, a shape-retaining member 26 is supported by generally U-shaped end frames 27 which rest on the bottom of the tank. The shape-retaining member is preferably cylindrical and is provided with V-shaped grooves 28 which alternate with slightly concave grooves 29. The distance between the grooves 28 which are nearest each other is preferably exactly the distance between adjacent grooves 16 in the bars 15. Similarly, the distance between each pair of grooves 29 should be equal to that between adjacent grooves 16. It is not necessary that the grooves 28 and 29 extend entirely around the member 26, it being sufficient that they be located only at the top of the member so that a previously grouped thread may be held in proper shape thereby.

Grooves 30 are provided at each end of the 75

shape-retaining member 26 to engage the upright portions of the end frame 27. A bolt 31 is screwed through a threaded hole 32 at each end of the member 26 and rests on the upper surface of the base of each frame 27. Turning the bolts 31 raises or lowers the member 26 to the desired height relative to the frames 27 and the bottom of the tank 1.

Longitudinal partition walls 33 are secured by 10 transverse grooved bars 34 to frameworks 35, thereby separating the apparatus into longitudinal channels.

For the production of generally flat or slightly concave multifilament rubber threads, an alternate set of grouping or forming bars 36 (Fig. 4) is provided with parallel end grooves 37, identical to the grooves 17 in the bars 15, whereby they may be inserted between the pins 18 in lieu of the bars 15. A handle 38 extends from the top 20 of each bar 36 for convenient insertion and withdrawal.

In operation, latex filaments 5 are streamed from the nozzles 3 into the coagulant bath 2 so that coagulation immediately commences. As each set of filaments 5 passes between the aligning pins 12 and 13, it is vertically aligned into a trio of filaments which passes within the groove 16 under the grouping or forming bar 15 which arranges the individual component filaments in triangular relationship into a composite, lightly adhered thread 40, partially coagulated. From beneath the grouping or forming bars 15, the thread travels within the triangular groove 28 in the shape-retaining member 26, which 30 serves to retain the triangular shape of the thread so that effective adhesion in their partially coagulated condition between the filaments is insured. From the member 26, the thread travels within the coagulant toward the end of 40 the tank to complete the adhesion of the filaments and to complete coagulation, if desired. The threads 6 are finally withdrawn from the tank over the roller 7 by suitable means (not shown), whence they may be subjected to washing, drying and vulcanizing steps. The means 45 for withdrawing the threads from the tank may be suitably adjusted so that the speed of the threads on withdrawal corresponds generally to the rate of speed of formation of the individual filaments, thereby preventing buckling or excessive stretching of the filaments or threads during their manufacture. Depending upon such factors as the rate of travel of the threads through the tank and the relative densities of 50 the latex filaments and the coagulant fluid, the height of the bars 15 may be adjusted relative to the shape-retaining member 26 for the smooth-est-running operation.

When a generally flat thread is desired, four nozzles 3 may be employed to produce filaments for the thread 42 shown in Fig. 6. A tri-filament generally flat thread, however, may be produced by the apparatus described above merely by substituting the slightly concave grouping bars 36 for the V-grooved bars 15, and by shifting the shape-retaining member 26 so that the slightly concave surfaces 29 assume the positions previously occupied by the V-shaped grooves 28. The alignment of the filaments below the grouping or forming member is clearly shown in Fig. 4.

The term "substantially flat multifilament rubber thread" as employed in this specification and the appended claims, designates a generally flat or planar cross-sectional arrangement of the individual filaments in the final composite thread

and does not refer to flattening of the surface of any individual filament. The term "generally triangular cross-section or configuration," as applied to the final composite thread, likewise refers merely to the arrangement of the filaments in the ultimate thread, and does not necessarily refer to the cross-sectional shape of any individual filament. As explained above, the present invention provides for the production of a multifilament rubber thread, of which the individual filaments are preferably round in cross-section at the outset, and are not deformed from their original shape at any stage in the process.

It is obvious, of course, that the number and shape of the nozzles 3 emerging from each pipe 4 may be varied as desired, and that the shape of the grouping surface may correspond to any desired grouping configuration of the filaments. For example, a rectangular forming surface may be provided in the grouping bar 5, and four or more filaments led therebeneath, resulting in a generally rectangular arrangement of the group of filaments comprising the composite thread.

The term "latex" as employed in this specification and the appended claims designates broadly coagulable dispersions of elastic materials including artificial dispersions of rubber or rubber-like materials as well as natural latex, which may be preserved or compounded or otherwise treated as desired, as by vulcanization, and which may be in normal, concentrated, diluted, or purified condition produced by methods well known in the art.

While certain exemplary methods and apparatus have been shown and described for carrying out the present invention, it is to be understood that it may be otherwise embodied within the spirit thereof and within the scope of the appended claims.

Having thus described my invention, what I claim and desire to protect by Letters Patent is:

1. In the method of producing a multifilament rubber thread, the steps comprising streaming latex through a plurality of nozzles into a liquid coagulating medium, drawing the filaments thus formed through said liquid medium beneath and in contact with a forming surface within said liquid medium, said forming surface being adapted to adhere the plurality of filaments together into a thread of the desired grouping configuration, and drawing the thus formed composite thread through the liquid coagulating medium.

2. In the method of producing a multifilament rubber thread of generally triangular cross-section, the steps comprising streaming latex through a plurality of nozzles into a liquid coagulating medium, drawing the filaments thus formed through said liquid medium beneath and in contact with a forming surface within said liquid medium, said surface having the general shape of an inverted V and being adapted to adhere the plurality of filaments together into a generally triangular thread, and drawing the thus formed composite thread through the liquid coagulating medium.

3. In the method of producing a substantially flat multifilament rubber thread, the steps comprising streaming latex through a plurality of nozzles into a liquid coagulating medium, drawing the filaments thus formed through said liquid medium beneath and in contact with a slightly concave and substantially horizontal forming surface within said liquid medium, said surface being adapted to adhere the plurality of fila-

ments laterally into a substantially flat thread, and drawing the thus formed composite thread through the liquid coagulating medium.

4. In the method of producing multifilament rubber thread, the steps comprising streaming latex through a plurality of nozzles into a liquid coagulating medium, drawing the filaments thus formed through said liquid medium beneath and in contact with a forming surface within said liquid medium, said forming surface being adapted to adhere the plurality of filaments together into a thread of the desired cross-sectional configuration, drawing the thus formed composite thread over a shape-retaining member within the liquid coagulating medium.

5. In the method of producing a multifilament rubber thread, the steps comprising streaming latex through a plurality of nozzles into a liquid coagulating medium, vertically aligning said filaments thus formed in said liquid medium, drawing the thus aligned filaments through said medium beneath and in contact with a forming surface within said medium, said forming surface being adapted to adhere the plurality of filaments together into a thread of the desired grouping configuration, and drawing the thus formed composite thread through the liquid coagulating medium.

6. In the method of producing a multifilament rubber thread of generally triangular cross-section, the steps comprising streaming latex through a plurality of nozzles into a liquid coagulating medium, vertically aligning the filaments thus formed in said liquid medium, drawing the thus aligned filaments through said medium beneath and in contact with a forming surface within said medium, said forming surface having the general shape of an inverted V and adapted to adhere the plurality of filaments together into a thread of generally triangular configuration, and drawing the thus formed composite thread through the liquid coagulating medium.

7. In the method of producing a substantially flat multifilament rubber thread, the steps comprising streaming latex through a plurality of nozzles into a liquid coagulating medium vertically aligning the filaments thus formed in said liquid medium, drawing the thus aligned filaments through said medium beneath and in contact with a slightly concave and substantially horizontal forming surface within said medium, said surface being adapted to adhere the plurality of filaments laterally into a substantially flat thread, and drawing the thus formed composite thread through the liquid coagulating medium.

8. In the method of producing a multifilament rubber thread, the steps comprising streaming latex through a plurality of nozzles into a liquid coagulating medium, vertically aligning the filaments thus formed in said liquid medium, drawing the thus aligned filaments through said medium beneath and in contact with a lower forming surface within said medium, said forming surface being adapted to adhere the plurality of filaments together into a thread having the desired cross-sectional configuration, and drawing the thus formed composite thread over a shape-retaining member within the liquid coagulating medium.

9. Apparatus for producing a multifilament rubber thread comprising a tank, a fluid medium within said tank, means for drawing a plurality of at least partially coagulated rubber filaments through said fluid medium, and grouping means intermediate the ends of the tank for

grouping such filaments, said grouping means comprising a member having a lower forming surface below the surface of said fluid medium adapted to adhere together into a thread of the desired grouping configuration a plurality of filaments being drawn through said fluid medium.

10. Apparatus for producing a multifilament rubber thread of generally triangular cross-section comprising a tank, a fluid medium within said tank, means for drawing a plurality of at least partially coagulated rubber filaments through said fluid medium, and grouping means intermediate the ends of the tank for grouping such filaments, said grouping means comprising a member having a lower inverted V-shaped surface below the surface of said fluid medium adapted to adhere together into a generally triangular thread a plurality of filaments being drawn through said fluid medium.

11. Apparatus for producing a substantially flat multifilament rubber thread comprising a tank, a fluid medium within said tank, means for drawing a plurality of at least partially coagulated rubber filaments through said fluid medium, and grouping means intermediate the ends of the tank for grouping such filaments, said grouping means comprising a member having a slightly concave and substantially horizontal lower forming surface below the surface of said fluid medium adapted to adhere together into a generally flat thread a plurality of filaments being drawn through said fluid medium.

12. Apparatus for producing a multifilament rubber thread comprising a tank, a fluid medium within said tank, means for drawing a plurality of at least partially coagulated rubber filaments through said fluid medium, grouping means intermediate the ends of the tank for grouping such filaments, said grouping means comprising a member having a lower forming surface below the surface of said fluid medium adapted to adhere together into a thread of the desired cross-sectional configuration a plurality of filaments being drawn through said fluid medium, and a shape retaining member having an upper surface below the surface of said fluid medium of a configuration corresponding to the configuration of said lower forming surface of said grouping member.

13. Apparatus for producing a multifilament rubber thread comprising a tank, a fluid medium within said tank, means for drawing a plurality of at least partially coagulated rubber filaments through said fluid medium, aligning means for such filaments comprising a plurality of substantially vertical bars arranged generally in the line of travel of such filaments, and grouping means intermediate the ends of the tank for grouping said filaments, said grouping means comprising a member having a lower forming

surface below the surface of said fluid medium adapted to adhere together into a thread of the desired grouping configuration a plurality of filaments being drawn through said fluid medium.

14. Apparatus for producing a multifilament rubber thread of generally triangular cross-section comprising a tank, a fluid medium within said tank, means for drawing a plurality of at least partially coagulated rubber filaments through said fluid medium, aligning means for such filaments comprising a plurality of substantially vertical bars arranged generally in the line of travel of such filaments, and grouping means intermediate the ends of the tank for grouping such filaments, said grouping means comprising a member having a lower inverted V-shaped surface below the surface of said fluid medium to adhere together into a generally triangular thread a plurality of filaments being drawn through said fluid medium.

15. Apparatus for producing a substantially flat multifilament rubber thread comprising a tank, a fluid medium within said tank, means for drawing a plurality of at least partially coagulated rubber filaments through said fluid medium, aligning means for such filaments comprising a plurality of substantially vertical bars arranged generally in the line of travel of such filaments, and grouping means intermediate the ends of the tank for grouping such filaments, said grouping means comprising a member having a slightly concave and substantially horizontal lower forming surface below the surface of said fluid medium adapted to adhere together into a generally flat thread a plurality of filaments being drawn through said fluid medium.

16. Apparatus for producing multifilament rubber threads comprising a tank, a fluid medium within said tank, means for drawing a plurality of at least partially coagulated rubber filaments through said fluid medium, aligning means for such filaments comprising a plurality of substantially vertical bars positioned generally in the line of travel of such filaments, grouping means intermediate the ends of the tank along such line of travel for grouping such filaments, said grouping means comprising a member having a lower forming surface below the surface of said fluid medium adapted to adhere together into a thread of the desired grouping configuration a plurality of filaments being drawn through said fluid medium, and a shape-retaining member along such line of travel having an upper surface below the surface of said fluid medium of a configuration corresponding to the configuration of said lower forming surface of said grouping member.

L. DEXTER ALDRICH.
